UNITED STATES PATENT OFFICE.

GLADSTONE RIGGS, OF BOTHELL, WASHINGTON, ASSIGNOR OF ONE-HALF
TO C. C. SILL, OF BOTHELL, WASHINGTON.

LIFTING-JACK.

SPECIFICATION forming part of Letters Patent No. 761,914, dated June 7, 1904.

Application filed June 24, 1903. Serial No. 162,951. (No model.)

To all whom it may concern:

Be it known that I, GLADSTONE RIGGS, a citizen of the United States of America, and a resident of the town of Bothell, in the county of King and State of Washington, have invented certain new and useful Improvements in Lifting-Jacks, of which the following is a specification.

My invention relates to improvements in lifting-jacks, and has special reference to a device of this nature in which the application of the power can be varied for a light or heavy lift.

Among numerous objects attained by this invention and readily understood from the following specification and accompanying drawings, included as a part thereof, is the production of a simplified and efficient lifting-jack embodying essential features of adjustability and utility throughout the operating mechanism, which allows for a variable application of the power to the lifting-bar and facilitates the operation thereof.

The above-mentioned and other desirable objects are attained by the constructions, combinations, and arrangements of parts as disclosed on the drawings, set forth in this specification, and succinctly pointed out in the appended claims.

With reference to the drawings filed herewith and bearing like reference characters for corresponding parts throughout, Figure 1 is a side view of the lifting-jack, with the standard, shown in longitudinal section, and the adjustable lever, shown by bold lines engaged with the lifting-bar and by broken lines engaged with the power-multiplying mechanism; and Fig. 2 is a plan view of the lifting-jack, with the standard, shown in horizontal section on line 2-2 of Fig. 1, and the adjustable lever engaged with the power-multiplying mechanism.

This invention includes a suitable support as a vertical standard 3, which is formed tubular and comprises a cylindrical section 4, rotatably mounted upon a base, as 5, and having a laterally-projecting bracket 6 at the upper end consisting of opposite side pieces 7,

preferably formed integral with the standard, which is cut away between these side pieces at suitable points to allow for engagement of the power-multiplying mechanism and check-pawl with the lifting-bar and is formed with a longitudinally-extending slot 8 in the wall opposite to said bracket. The lower end of this standard is formed with a head and fits freely within an annular flange 5', formed on base 5, and a bolt 6' is engaged in suitable corresponding apertures in said head and base and serves to hold the base to the standard when the jack is raised from the ground.

Fitting in the bore of standard 3 is a longitudinally-movable lifting-bar 9, which is provided with rack-teeth 10 along one side of the periphery, and at the lower end of this bar opposite the teeth is secured a laterally-projecting spur 12, which fits slidably in slot 8 and is curved upwardly at the outer extremity and sharpened at the end, so that the spur will readily bite into logs or timbers resting on flat planes for the purpose of lifting them at the ends, for example, so that skids or blocks can be readily placed beneath them.

Operatively connected with lifting-bar 9 is power-multiplying mechanism comprising a train of spur-gears, which includes a power-pinion 11, engaged with teeth 10 and secured to a spindle 14, rotatably supported in suitable apertures formed in side pieces 7, and to one end of this spindle is secured an intermediate spur-wheel 15, which is located at one side of bracket 6 and meshes with an intermediate spur-pinion 16, secured to a spindle 17, rotatably supported in suitable apertures formed in side pieces 7 and carrying a fixedly-mounted driver 18 intermediate said side pieces consisting of a spur-gear.

Reference character 19 indicates a toothed member for operating the lifting-bar and includes a lever, which is adjustably mounted relatively to the lifting-bar and the driver of the power-multiplying mechanism and carries a gear-sector 20 at the load end of suitable pitch to mesh with the teeth on said bar or the teeth on said driver. This lever is fulcrumed on an adjustable carrier 21, on

which the fulcrum-pin 22 for the lever is mounted and which comprises opposite links movably mounted between side pieces 7 on a pivot 23, seated on said side pieces adjacent 5 their outer upper corners, and these links carry the fulcrum-pin 22 adjacent their free ends and embrace said lever.

Adjacent the lower edge of bracket 6 is a spring-pressed catch-pawl 24, which is 10 formed with two fingers 25, spaced apart in accordance with the pitch of teeth 10 and beveled at their lower outer corners, so as to ride said teeth as the lifting-bar is moved outwardly. This pawl is suitably slidably mounted 15 on a shelf, as 26, and is pressed by a spring, as 27, arranged to yieldingly hold the pawl in engagement with said teeth, and a trip 28, consisting of a transversely-disposed horizontal bar, is engaged with the head of 20 said pawl and slidably fits in suitable elongated slots 7', formed in side pieces 7, and is formed with a suitable finger-piece 29, by means of which the pawl is moved outwardly to disengage it from the teeth 10 when desired to drop the lifting-bar.

By adjustably mounting the operating-lever it can be shifted relatively to the lifting-bar or driver of the power-multiplying mechanism so that the lifting-bar can be operated 30 for light loads or quick outward adjustment by applying the lever thereto direct, and when desired to raise a comparatively heavy load the lever can be applied to the driver of the power-multiplying mechanism, while the 35 spur on the lifting-bar renders the device useful in lifting logs, as before described, and by rotatably mounting the standard on the base it can be turned when the spur is so engaged to advance the lifted end of the timber 40 or log.

The operation of the jack will be readily understood from the foregoing description and accompanying drawings; but, briefly stated, it would be as follows: When desired to 45 lift a light load or adjust the lifting-bar outwardly, the carrier 21 is swung upwardly to bring the gear-sector of the operating-lever into engagement with the teeth on the said bar, and the lever is then operated to raise 50 the lifting-bar, and to clear the levers from said teeth for return it is simply necessary to swing said carrier outwardly a slight distance. When a heavy load is to be lifted, the carrier is swung outwardly to bring the lever into operative relation to the driver of the power-multiplying mechanism, when it is 55 operated as before to drive said mechanism.

This lifting-jack is simple and inexpensive of construction and durable in use and possesses marked advantages of adjustment, which 60 greatly facilitates the work of lifting, as it permits of direct application of the lever for quick movement of the lifting-bar in light work and the application of the lever through

power-multiplying mechanism for heavy 65 work.

Having thus described my invention, what I claim as new, and desire to secure by Letters Patent of the United States of America, is—

1. In a lifting-jack; the combination of a toothed lifting-bar, power-multiplying mechanism operatively related to said bar, and a shiftable lever adapted for either direct engagement with the teeth on said bar or for engagement with said mechanism.

2. In a lifting-jack; the combination of a toothed lifting-bar, power-multiplying mechanism including a gear engaging with the teeth on said bar, and a lever adjustable for engagement with the teeth on said bar or with said mechanism.

3. In a lifting-jack; the combination of a toothed lifting-bar, a train of gears operatively connected with the teeth on said bar, and a toothed member adjustably mounted for engagement with said bar or with the driving-gear of said train.

4. In a lifting-jack; the combination of a toothed lifting-bar, a train of gears one of which meshes with the teeth on said bar, a catch-pawl related to said bar, and a toothed lever adjustable for engagement with said bar or with the driving-gear of said train.

5. In a lifting-jack; the combination of a toothed lifting-bar, a train of gears one of which meshes with the teeth on said bar, and a lever carrying a gear-segment and adjustably mounted for engagement of said segment with the teeth on said bar or with the driving-gear of said train.

6. In a lifting-jack; the combination of a toothed lifting-bar, a train of gears one of which meshes with the teeth on said bar, a carrier adjustable relatively to said bar and the driving-gear of said train, and a lever fulcrumed on said carrier.

7. In a lifting-jack; the combination of a toothed lifting-bar, a train of gears one of which meshes with the teeth on said bar, a carrier adjustable relatively to said bar and the driving-gear of said train and comprising pivotally-mounted links, a fulcrum-pin on said links, and a lever carrying a gear-sector mounted on said pin.

8. In a lifting-jack; the combination of a toothed lifting-bar, a rotatably-mounted spindle, a power-gear meshing with the teeth on said bar and fixed to said spindle, an intermediate wheel fixed to said spindle, a second rotatably-mounted spindle, a pinion meshing with said wheel and fixed to said second spindle, a driving-gear fixed on said second spindle, a carrier adjustable relatively to said bar and the driving-gear of said train and comprising pivotally-mounted links, a fulcrum-pin on said links, and a lever carrying a gear-sector mounted on said pin.

9. In a lifting-jack; a base, a tubular stand-

ard rotatably mounted on said base and having a longitudinally-extending slot in the wall, a lifting-bar fitting in the bore of said standard, and a spur secured to said bar at the lower 5 end and projecting from said slot.

10. A standard having a bracket at the upper end comprising opposite laterally-projecting side pieces, a toothed lifting-bar fitting in the bore of said standard, a spindle rotatably mounted on said bracket, a power-gear between said side pieces secured to said spindle and meshing with the teeth on said bar, an intermediate wheel secured on said spindle at one side of said bracket, a second spindle rotatably mounted on said bracket, a pinion secured to said second spindle and meshing with said wheel, a driving-gear secured to said second spindle between said side pieces, a carrier comprising opposite links pivotally mounted 20 on said bracket, a fulcrum-pin on said links, a lever mounted on said pin and carrying a gear-sector, and a spring-pressed catch-pawl

mounted on said standard and normally engaging with the teeth on said base.

11. In a lifting-jack; a standard, a toothed 25 lifting-bar slidably mounted on said standard and having opposite laterally-projecting side pieces formed with corresponding outwardly-extending slots, a horizontally-disposed spring-pressed catch-pawl slidably mounted 30 between said side pieces and having fingers beveled at their lower outer corners and spaced apart in conformity with the pitch of the teeth on said standard, and a trip comprising a transversely-disposed bar connected with said 35 pawl and slidably mounted in said slots and having a finger-piece at one end.

Signed at Seattle, Washington, this 4th day of June, 1903.
